COMBINED DOUBLE-COLOR MECHANICAL
PENCIL AND FOUNTAIN PENIichi Hayashida, Ishihara-machi, Honjo-ku,
Tokyo, JapanApplication March 3, 1933, Serial No. 659,567
In Japan March 5, 1932

1 Claim. (Cl. 120—14)

This invention relates to a writing instrument adapted to be used as a fountain pen on one hand, and as a double-color mechanical pencil on the other hand.

5 The object of the invention is to provide a combined double-color mechanical pencil and fountain pen which is self-contained, comprising a barrel of fountain pen and pencil portion detachably inserted into one end of said barrel, 10 said pencil portion being adapted to alternately feed out two leads of different colors by rotating same in either direction.

With the above-mentioned object in view, the device according to this invention comprises a 15 barrel, an ink sac and a pen nib mounted in and to one end of said barrel, and a pencil assembly consisting of a conical head, a guide bar secured to said conical head and adapted to guide two lead-propelling members, a right and left hand 20 screw threaded tube mounted for rotation about said guide bar, and a sleeve enclosing said screw threaded tube, said sleeve and tube being projected outside the conical head and detachably inserted into the other end of the said barrel.

25 In the accompanying drawings, illustrating what I now consider the preferred form of my invention,

Figure 1 is a longitudinal section of the combined mechanical pencil and fountain pen made 30 according to this invention;

Figure 2 is an elevation thereof partly in section, with the pencil portion detached from the barrel;

Figure 3 shows a pencil nozzle;

35 Figure 4 is a cross section taken on line IV—IV of Figure 3;

Figure 5 is a cross section taken on line V—V of Figure 2;

Figure 6 is a lower end view of the pencil portion;

Figure 7 is a view similar to Figure 6, but with a cover for lead magazine opened;

Figure 8 is a perspective view showing lead propelling means;

45 Figures 9-11 show slightly modified forms of the invention.

Referring to the drawings, 1 is the barrel containing in one half thereof an ink sac 2. A head 3 to which said ink sac 2 is connected is screwed 50 to one end of the barrel and carries a pen nib 4. 5 is a cap, and 6 is a presser lever for actuating the ink sac 2.

In another half of the barrel 1 is formed a socket 7 for receiving the pencil portion, the upper end of said socket being enlarged as at 8.

9 is a conical pencil head having a nozzle 10 screwed thereto. As shown in Figures 3 and 4, this nozzle 10 is provided with a threaded portion 11 which is slotted at 12 so as to ensure a resilient engagement of said portion 11 with the 15 head 9 thereby preventing the nozzle 10 from being loosened or detached. 13 is a hollow guide bar approximately 8 shaped in cross section, as shown in Figure 5. This guide bar 13 is provided on opposite sides with longitudinal guide 10 channels and its looped portions constitute a lead magazine. One end of said guide bar 13 is secured to the conical head 9, and the channels on opposite sides thereof serve as guides for lead propelling members 14 which are adapted to slide 15 along said guide channels in the bar 13. As shown in Figure 8, each of the lead propelling members 14 is provided at its back with an inclined projection 15, and has a flexible rod 16 secured thereto, said flexible rod comprising a 20 plurality of metallic wires twisted together. At the other end of said flexible rod 16 is secured a lead clamping tube 17. 18 is a tube having right and left hand screw threads struck up from the inner side of the tube and of concavo- 25 convex section and rotatably mounted outside of and concentric with the guide bar 13. To the lower end of said tube 18 is secured a washer 19 formed with ports or openings 22 coincident with the tubular passages in the guide bar 13, constituting the lead magazine. A sleeve 20 is mounted outside and concentric with the threaded tube 18, and its lower end is closed by movable cover disc 21, by which the inlet ports 22 to the lead magazine are closed or opened, as shown 30 in Figures 6 and 7. The socket 7 is shown in the form of a tube having its inner end closed, and is simply a lining to the barrel with which it is in tight contact. This lining may obviously be omitted and the tube 20 inserted in the open 35 end of the barrel.

In Figures 10 and 11 are shown embodiments in which the sleeve 20 is provided on its outer surface a plurality of longitudinal ribs 24 so that a soft sliding movement of the sleeve 20 is ensured. Also a plurality of longitudinal ribs 25 may be formed on the inner surface of the barrel 1 as shown in Figure 10.

According to this invention, when the device is used as a fountain pen, the cap 5 is removed 50 and ink is filled in the sac 2 by manipulating the presser lever 6 in usual manner. When the device is used as a pencil, the conical head 9 is rotated clockwise or counter-clockwise, whereby the two lead propelling members 14 will be alternately 55

driven, so that the desired one of the two different leads may be propelled at will. Inasmuch as one half of the screw tube 18 extending out of the head 9 is surrounded by the sleeve 20 which is firmly inserted into the socket 7 in the barrel 1, the screw tube 18 is relatively rigidly mounted with respect to the barrel 1 and the guide bar 13 is rotated in unison with the propelling member 14 with respect to the screw tube 18 during the rotation of the head 9, thus the lead propelling member 14 slides along the longitudinal guide slots. The relative rotation of the conical head 9 with respect to the barrel 1 is mainly effected at the shoulder 23 and, inasmuch as the screw tube 18 and the sleeve 20 are firmly held in the socket 7 in the barrel 1, the rotational movement is adjusted solely by the degree of frictional contact at the shoulder 23. Consequently, at said shoulder portion the inner surface of the head 9 and the outer surface of the sleeve 20 which co-operate with each other should be so machined that there will not be any tendency of producing accidental free rotation of the two parts, and on the other hand ensuring a smooth rotation when intentionally operated. Said shoulder 23 is provided for the purpose of preventing any offsetting at the point of connection between the head 9 and the barrel 1.

Inasmuch as the tube 20 is held tightly in the barrel by close frictional contact with the latter, resisting the rotation of the tube 20, and the latter is in similar contact with the threaded tube 18, said sleeve and tube will not turn with the conical head. They may however be withdrawn from the barrel lengthwise of the latter, the washer 19 being attached to the guide bar, 13, and the latter attached to the conical head 9, and the guide bar and disc 21 connected together, whereby when the conical head is removed lengthwise of the barrel the guide bar, tube 18 and sleeve 20 will be removed therewith thus allowing access to the

lead magazine for replenishing the latter, or withdrawing its contents. The spare leads are prevented from falling out of the magazine by the pivoted cover 21.

It will be understood that, owing to the arrangement of the screw tube 18 and the sleeve 20 which protrude from the conical head 9 and are inserted into the socket 7 in the barrel, the rotatable mounting of said conical head 9 may be readily effected, and that such rotation can be made smooth and adjustable. Moreover, owing to said special arrangement, the pencil portion can be readily removed from the barrel 1 so that the spare lead may be taken out of the magazine by opening cover 21.

What I claim is:—

A double color mechanical pencil comprising a barrel having a socket formed at one end thereof and a pencil assembly consisting of a tapering head rotatable on said barrel, a hollow guide bar having oppositely arranged channels for the reception and movement of lead propelling members, and open ended tubular portions constituting lead magazines, said guide bar being attached to said head, a screw threaded tube having right and left handed screw threads intersecting each other, two lead propelling members arranged and adapted to be moved in said channels, and to engage with the threads of the screw threaded tube and ride thereon, a sleeve surrounding and closely fitting said screw threaded tube and inserted in the socket of the barrel, a closure for the inner end of the guide bar, having ports coinciding with the open ends of said magazines, a pivotally arranged cover for the ends of said magazines, attached to said sleeve, the said threaded tube and sleeve being in substantially tight frictional contact to prevent rotation with the conical head, but slidably longitudinally to permit withdrawal from the barrel.

EIICHI HAYASHIDA.
